COMBINATION BRUSH HOLDER AND PAINT
CAN HANDLE

Clarence G. Davis, Tracyton, Wash.

Application August 10, 1948, Serial No. 43,361

5 Claims. (Cl. 224—45)

1

This invention relates to a combination brush holder and paint can handle, and is in the nature of an improvement upon the brush holding devices of my co-pending application filed on October 13, 1947, under Serial No. 779,540, in that it combines with a brush holder, a handle or holder for a paint can.

It is the principal object of my invention to provide a simplified and inexpensive device of the above stated kind, that will effectively serve its intended purposes.

More specifically stated, the objects of the invention reside in the provision of a brush holder and can handle that is in the nature of a spring clamp, formed from a single piece of resilient sheet metal, and comprising a vertical body portion that is adapted to engage flatly against the side wall of a paint can, with its upper end portion extended above the can rim and formed with an opening designed to receive the handle of a brush therethrough in a manner whereby to hold the brush in position to drain or drip into the can; said vertical body portion being joined at its lower end with an outwardly and then upwardly directed handle forming portion which, at its upper end, is turned inwardly to extend through and beyond the said opening and formed with a hook to holdingly engage with the cover seating flange in the upper end of the can, thus to secure the device functionally in place.

It is also an object of the invention to provide a device of the character above stated that, when applied in use, will be placed under yielding tension and, by reason of this tension, will retain itself against release from the can under all normal conditions of use.

Still further objects of the invention reside in the details of construction and relationship of parts embodied in the device, and in its mode of application and use, as will hereinafter be fully described.

In accomplishing these and other objects of the invention, I have provided the improved details of construction, the preferred forms of which are illustrated in the accompanying drawings, wherein:

Fig. 1 is a perspective view showing a brush holder and can handle embodied by the present invention as functionally applied to a paint can.

Fig. 2 is a side view of the can with brush holder applied thereto; a part of the can body being broken away for better illustration and understanding of the manner of securing the brush holder.

Fig. 3 is a top view of a part of a can, showing

the present brush holder and handle member applied thereto.

Fig. 4 is a section taken on line 4—4 in Fig. 2. Referring more in detail to the drawings: The present device, which is designated in its entirety by numeral 10, is made from a single and continuous piece, or strip of resilient metal, such as sheet steel, bent in a manner to provide a main body portion of U-shape; one leg of this body portion, referred to as the inner leg and designated by numeral 11, being designed to engage flatly against and to extend vertically along a side wall of a paint can, or the like, as has been illustrated in Figs. 1 and 2. The outer leg of this body portion, designated by reference numeral 12, is joined to the inner leg by the curved base portion 13 of the U-shaped body. The resiliency of the metal of the base portion permits the outer leg to be sprung inwardly at its upper end toward the inner leg for a purpose presently apparent.

The upper end portion of the inner leg of the U-shaped body designated by reference numeral 14 is curved outwardly and upwardly, as shown best in Fig. 2, and has the central portion cut away, or removed, thus to provide an opening 15 of such size that the handle of a paint brush may be projected therethrough, as has been shown best in Fig. 1. When the device is applied to a can, the lower edge of this opening is at the level of the top of the can.

The upper end portion of the outer leg of the body, designated at 16, is reduced in width as shown best in Fig. 3 and is bent directly inwardly, to pass through the lower end portion of the opening 15, and at its inner end is provided with a downwardly and outwardly turned hook portion 17; this hook portion being in opposed clamping relationship to the upper end portion of the leg 11 as will be understood by reference to Fig. 2.

With the device so formed, it is applied and used as follows, it being understood that it is intended for use with the present day types of paint cans of the type illustrated.

First, the cover or lid of the paint can is removed, thereby leaving the cover seating flange exposed for the application of the securing hook of the present device thereto. In Figs. 1 and 2, the paint can is designated by numeral 20, and the cover seating flange, which extends inwardly from the upper end seam 21 of the can body side wall, is designated by numeral 25.

The U-shaped body member of the present device is then placed flatly against the side wall

of the can substantially as shown in Fig. 1; the leg portion 11 being disposed vertically and approximately even at its upper end with the upper end seam. Then the upper end portion of the outer leg of the body is pressed toward the can until the hook 17 is within the inner rim of the flange 25. Then the device is bodily shifted downwardly and the inward pressure against the leg 12 is released so that the hook 17, will engage with the flange 25 as in Fig. 2. The U-shaped body thus being securely attached to the can by the hook 17 serves as a handle for holding, carrying or handling of the can. The tension under which the hook 17 is engaged with the flange will at all times keep the device securely clamped against the can body wall.

To insure the handle against any lateral turning or rocking action on the can body, the inner leg 11 is transversely and outwardly cupped or arched, as has been shown at 28 in Fig. 4, so that the leg 11 will engage the can wall only along its longitudinal edge portions.

After a paint brush such as shown at 30 in Figs. 1 or 2 has been used, should it be desired to hold it over the can so that the can will catch the drip therefrom, the brush handle portion is extended through the opening 15 of the outwardly curved upper end portion of the inner leg, to rest near the brush head upon the inner end portion of the inwardly directed part 16, and to engage against the member across the top of the opening 15. The relationship and formation of these various parts of the device is such that the brush will be supported above the normal level of paint in the can as has been shown in Fig. 2. Thus the device has the dual purpose of brush holder and can handle.

The device may be readily detached to permit closing the can merely by pressing the outer leg inwardly to disengage the hook 17 from flange 25 so that the device can be lifted free.

Such devices may be made in various sizes to adapt them for use on cans of large or small size. However, one size will readily accommodate cans of a wide range of sizes.

Having thus described my invention, what I claim as new therein and desire to secure by Letters Patent is:

1. A combination paint brush holder and handle comprising a body member, substantially of U-shape, adapted to be disposed with the inner leg portion thereof vertically engaged against the side wall of a can, and its outer leg spaced outwardly from the can as a hand hold; said inner leg portion having an upper end extension 50 designed to project above the top edge of the

can and formed with an opening for the reception of the handle portion of a brush therethrough to hold the brush, and the said outer leg having a part turned inwardly from its upper end, and engaged in holding contact with the top edge of the can thus to functionally secure the device to the can.

2. A combination paint brush holder and handle comprising a resilient body member, substantially of U-shape, adapted to be disposed with the inner leg portion thereof vertically engaged against the side wall of a can and its outer leg portion spaced outwardly from the can as a handle therefor, said inner leg portion having an upper end extension designed to project above and outwardly from the top edge of the can and formed with an opening for the reception of the handle portion of a paint brush therethrough to hold the brush head over the can, and the said outer leg portion of the body member having a part turned inwardly therefrom and formed at its inner end with a hook to engage in holding contact over the top edge of the can to secure the device thereto.

3. A combination paint brush holder and handle comprising a body member, formed from a continuous strip of resilient sheet metal, bent to provide a body portion of U-shape, adapted to be disposed with its inner leg portion engaged flatly and vertically against the side wall of a paint can or the like; said inner leg portion having an extension at its upper end extending outwardly and upwardly from the can and formed with an opening of substantial size for the passing of the handle portion of a brush therethrough to support the brush over the can, and said outer leg having a portion turned directly inwardly therefrom and passed through the bottom portion of said opening and formed with a downwardly and outwardly turned hook to engage in holding contact over the top edge and flange of the can to secure the device to the can.

4. A device as recited in claim 3 wherein the U-shaped body is of resilient metal and the said U-shaped body is applied to the can under such compression that the said hook is yieldingly clamped over the can flange.

5. A device as recited in claim 3 wherein the inner leg of the U-shaped body member is transversely arched to bear in line contact along its opposite edges with the can body wall.
